UNITED STATES PATENT OFFICE.

RAYBURN CLARK SMITH, OF PHILADELPHIA, PENNSYLVANIA.

DESIGN FOR A WALL PANEL OR PARTITION.

49,230.

Specification for Design.

Patented June 20, 1916.

Application filed February 23, 1916. Serial No. 80,072. Term of patent 7 years.

To all whom it may concern:

Be it known that I, RAYBURN CLARK SMITH, a citizen of the United States, residing at Philadelphia, county of Philadelphia, and State of Pennsylvania, have invented a new, original, and ornamental Design for a Wall Panel or Partition, of which the following is a specification, reference being had to the accompanying drawing, forming a part thereof, wherein the figure is an

elevation of my new design for a wall panel or partition.

I claim:

The ornamental design for a wall panel or partition, as shown.

RAYBURN CLARK SMITH.

Witnesses:

FRANK L. RICE,
L. J. RICHARDSON.
